CLAIM

(57) The ornamental design for a container with sleeve, as shown and described.

DESCRIPTION

FIG. 1 is a perspective view of a first embodiment of a container showing our new design;

FIG. 2 is a top plan view thereof;

FIG. 3 is a left elevation view thereof;

FIG. 4 is a right elevation view thereof;

FIG. 5 is a back elevation view thereof;

FIG. 6 is a front elevation view thereof;

FIG. 7 is a perspective view of a second embodiment of a container showing our new design;

FIG. 8 is a top plan view thereof;

FIG. 9 is a left elevation view thereof;

FIG. 10 is a right elevation view thereof;

FIG. 11 is a back elevation view thereof; and,

FIG. 12 is a front elevation view thereof.

The broken line portion of the container in the figure drawings is included to show unclaimed subject matter only and forms no part of the claimed design.
